CLAIM

The ornamental design for a mouse pad in the shape of a baseball jersey, as shown and described herein.

DESCRIPTION

FIG. 1 is a perspective view of a mouse pad in the shape of a baseball jersey.

FIG. 2 is a front elevational view of a mouse pad in the shape of a baseball jersey.

FIG. 3 is a rear elevational view of a mouse pad in the shape of a baseball jersey.

FIG. 4 is a top view of a mouse pad in the shape of a baseball jersey.

FIG. 5 is a bottom view of a mouse pad in the shape of a baseball jersey.

FIG. 6 is a left side view of a mouse pad in the shape of a baseball jersey; and,

FIG. 7 is a right side view of a mouse pad in the shape of a baseball jersey.

The elements illustrated in dashed lines in the accompanying drawings are considered environmental and do not form a part of the claimed design.
